Inventor

UNITED STATES PATENT OFFICE.

JAMES S. CONWAY, OF ROCHESTER, MINNESOTA.

WRENCH.

Application filed October 20, 1923. Serial No. 669,848.

To all whom it may concern:

Be it known that I, JAMES S. CONWAY, a citizen of the United States, residing at Rochester, in the county of Olmsted and 5 State of Minnesota, have invented certain new and useful Improvements in Wrenches, of which the following is a specification.

The present invention relates to a wrench and has for its principal object to provide 10 a device of this nature constructed so that it may grasp different sized objects within a considerable range.

Another important object of the invention is to generally improve upon wrenches of 15 this nature by providing a device possessed of a simple and efficient construction, one which is reliable, inexpensive to manufacture, durable, compact, easily manipulated, and well adapted for the purpose designed.

20 With the above and numerous other objects in view which will appear as the description progresses, the invention resides in certain novel features of construction, and in the combination and arrangement of 25 parts as will be hereinafter more fully described and claimed.

In the drawings:

Figure 1 is a side elevation of the wrench embodying my invention; and 30 Figure 2 is an edge elevation thereof.

Referring to the drawing in detail it will be seen that the shank A is formed in two bars 1 which extend in substantial parallelism with each other being offset intermediate 35 their ends as at 2 so that portions thereof are spaced from each other and the other portions thereof held together in a suitable handle 3. A fixed jaw 4 is disposed between the spaced portions of the bars 1 by means 40 of a rivet 5 or any other suitable device. This fixed jaw 4 is provided with an outer serrated curved engaging jaw 6. A pair of rods or links 7 are pivoted on a bolt 8 passing through the spaced portions of the bars 1 and the fixed jaw 4. A movable jaw 9 is fixed to the ends of these links 7 as at 45 10 and is provided with a curved serrated engaging face 11 on its inner side. Particular attention is called to the fact that the curved 50 surface 6 of the fixed jaw is formed eccentric in relation to the pivot 8 of the links 7 thereby forming a cam surface from which it will be seen that when a member is dis-

posed between the jaws as illustrated in Figure 1 and the handle 3 moved to the right that said jaws 6 and 9 will tend to move toward each other thereby gripping the object firmly. Considering the device as shown in Figure 1 it will be seen that by moving the movable jaw 9 to the left the distance between the two jaws may be varied and will become greater as the jaw is moved in this direction and vice versa. It is evident that this wrench may be used in the same manner as an ordinary Stilson wrench and will be much more efficient since it will be self adjustable to the size of the object within a reasonable range.

Although I have described my invention with a certain degree of particularity, it is 70 to be understood that numerous changes in the details of construction and in the combination and arrangement of parts may be resorted to without departing from the spirit or scope of the invention as herein-after claimed without sacrificing any of its advantages.

What is claimed is:

1. A wrench comprising a shank which includes a pair of spaced parallel bars, a longitudinally curved jaw arranged between the outer ends of the bars and extending at an oblique angle with respect thereto, a securing pin passing through the bars and jaw intermediate the ends of the latter, a pivot pin passing through the bars and jaw adjacent its inner end, a pair of links pivotally supported on the ends of the pivot pin and a longitudinally curved jaw rigidly held between the links and being movable in a plane parallel to the fixed jaw.

2. A wrench of the class described including a handle, a pair of rods extended into the handle and fixed thereto, portions of the rods extending in spaced relation to each other from the handle, a jaw fixed between the terminals of the spaced portions of the rods and provided with a curved serrated engaging face, a pair of links pivoted to the jaw at a point off center in relation to the curve of the engaging surface, and a jaw fixed between the terminals of the links and provided with an inner serrated curved face for cooperation with the curved face of the first jaw all in the manner and for the purpose specified.

3. A wrench comprising a pair of spaced parallel bars, a handle carried by one end thereof, a longitudinally curved jaw rigidly supported by the outer ends of the bars and 5 extending at an oblique angle with respect thereto, a pair of links pivoted to the inner end of the jaw, and a longitudinally curved

jaw rigidly carried by and between the outer ends of the links, said jaw being movable in a plane parallel to the first mentioned jaw. 10

In testimony whereof I affix my signature.

JAMES S. CONWAY.
